BOILER

John H. Lawrence, Bronxville, N. Y., assignor to
 Metropolitan Engineering Company, Brooklyn,
 N. Y., a corporation of New York

Application March 21, 1936, Serial No. 70,013

4 Claims. (Cl. 122—187)

The invention aims to provide a boiler in which a comparatively large area of heating surface is provided in a compact structure. It is thus particularly adapted to boilers for household use where economy of space is important. By the provision of a large heating surface it also serves to heat the water or generate steam quickly and at a high rate.

The accompanying drawings illustrate an embodiment of the invention.

Fig. 1 is a longitudinal section through a boiler and furnace. Fig. 2 is a horizontal section through the water chamber and heating and circulating pipes. Fig. 3 is a vertical section approximately on the line 3—3 of Fig. 2.

The main casing comprises a cylindrical shell 1 with a dome 2. In the lower part of the casing is a smaller shell 3 constituting the furnace, adapted to take the usual grate or oil or gas burners and attachments. A door 4 admits the fuel or the burners. The heating gases pass out through openings 5 at the opposite side. Between the outer casing 1 and the furnace wall 3 is a downwardly extending leg or space 6 communicating with the larger water chamber 7 above the dome 8 of the furnace.

The door 4 and exits 5 from the furnace are in the form of tubes spanning the water leg 6. The water chamber is provided with any usual or suitable couplings and other details for the feeding and the circulating attachments.

The present invention is directed particularly to the heating of the water. For this purpose there is a supplementary chamber 9 in a casing 10 fixed on the back of the main casing 1, communicating at its lower end with the furnace through the exit tubes 5 and having an opening 11 at the top leading to the smoke pipe or chimney. Within the chamber 9 are sections of boiler tubing 12 which in plan are concentric or parallel to the back wall of the casing, as in Fig. 2, and which in elevation are inclined as in Fig. 3. The ends of the tubes 12 are bent inward and enter the casing 1 so as to communicate with the main water chamber. The hot gases traveling over these tubes heat the water therein causing it to flow into the main water chamber at the higher ends of the tubes and from the water chamber into the tubes at their lower ends thus heating and circulating the water in the main chamber.

The heating surface is greatly increased by means of projections 13 welded to the portions of the tubes within the chamber 9. These projections are in the form of small fins extending a considerable distance radially outward from the

tubes and having comparatively small ends welded to the tubes separately; thus avoiding the strains in welding and in use which would occur with welded joints of any considerable length.

By providing numerous projections separately welded but closely spaced to each other along the lengths of the tube and also circumferentially, and extending a considerable distance radially outward from the tube, a very great and most effective heating surface is provided beyond that which could conveniently be secured by the ordinary method of passing the heating gases through tubes within the water chamber. We have, in fact, with the approximate compactness of the ordinary fire tube boiler the greater heating effect obtainable in water tube boilers. There being no fire tubes through the main water chamber 7, the dimensions of this chamber may be made considerably smaller for a given volume of water, thus compensating in a measure for the extra space taken by the casing 10.

In the case illustrated, if the tubes 12 are assumed to be of two inch diameter, then for every lineal foot of these finned tubes we can secure 555 square inches of heating surface, taking the projections to be as illustrated. Four feet of such tubing, or say three 18 inch lengths thereof (4½ feet) will provide a heating area equal to that of an ordinary sized house heating boiler. Thus the completed boiler is compact notwithstanding the supplementary chamber.

The supplementary casing with its finned tubes therein may be manufactured as a separate unit adapted to fit against the outside of the boiler casing and to be welded thereto as shown, it being necessary only to provide holes in the outer casing 1 of the boiler for the ends of the tube sections 12, the shell 1 of the main casing constituting one wall of the supplementary chamber. The two chambers 7 and 9 are thus closely coupled and are also united in operation, the heat units being applied almost wholly in the part 9 where they are most effective and being there applied to cause a high heating as well as a forceful circulation of the water in the two chambers.

Where insulation is to be used it may be applied after the supplementary casing is fixed on to the main casing. For example, Fig. 2 shows the completed structure enclosed in an insulating compound 14 held in place by a steel jacket 15; the insulation being continuous around the assembled structure, though partly broken away in the drawings.

The steam or hot water outlet pipe will be attached to the coupling 16, the return pipe for

condensed steam or feed water will be attached to the coupling 17. The small tubes 18 and 19 are for application of pressure gauge, pressure regulator and other usual attachments. The 5 boiler generally is of a standard type similar to that described in a co-pending application of Henry S. Holmes, Ser. No. 68,605, filed March 13, 1936; the supplementary heating chamber with water circulating tubes being substituted for the 10 internal fire tubes which pass back and forth through the main water chamber in said Holmes application.

Various modifications may be made by those skilled in the art without departing from the 15 invention as defined in the appended claims.

What I claim is:

1. A boiler having a furnace, a main water carrying chamber above the furnace, a relatively narrow heating chamber extending upwardly adjacent 20 a portion of the outer surface of said water carrying chamber for the upward passage of gases therethrough, and a number of water heating tubes in said chamber transverse to the passage of gases therethrough and approximately 25 parallel to the surface of said water carrying chamber, and connected to said water carrying chamber at their opposite ends at different levels.

2. A boiler having a furnace, a main water carrying chamber above the furnace, a heating 30 chamber extending upwardly from said furnace alongside an outer wall of said water chamber for the upward passage of gases therethrough, a vertical series of water heating tubes transverse to the passage of gases through said passage 35 and approximately parallel to the surface of said water carrying chamber, each tube being connected at its opposite ends to said water chamber at different levels, and each tube being provided with fins projecting outwardly in planes

at right angles to the center line of their respective tubes, said projections being narrow plates extending outwardly from their respective tubes at angles of approximately 45° to the horizontal and extending through the spaces between said tubes and the walls of said passage. 5

3. A boiler having a furnace, a main water carrying chamber above the furnace, a relatively narrow heating chamber extending upwardly adjacent a portion of the outer surface of said water carrying chamber for the upward passage 10 of gases therethrough, and a number of water heating tubes in said chamber transverse to the passage of gases therethrough and approximately parallel to the surface of said water chamber and 15 connected to said water carrying chamber at their opposite ends at different levels, said tubes having fins projecting outwardly at planes intersecting their respective center lines in the spaces between said tubes. 20

4. A boiler having a furnace, a main water carrying chamber above the furnace, a heating chamber through which the hot gases pass directly from the furnace, water tubes in said heating chamber closely spaced from and approximately paralleling the surface of said main chamber, having their opposite ends above the furnace and communicating with the main chamber and being highly heated by the passage of such gases so as to cause the water to circulate 30 forcefully through said chamber and said tubes, the casing of the main chamber having a downward extension around the furnace wall and spaced away therefrom so as to form a water leg communicating with the main water chamber, a feed water connection at the bottom of 35 said water leg, and a steam or hot water outlet pipe at the top of the main chamber.

JOHN H. LAWRENCE.
